DESIGN FOR A DRAFT YOKE

Wiley C. McMahan, Heflin, Ala.

Application July 9, 1935, Serial No. 57,577

Term of patent 7 years

To all whom it may concern:

Be it known that I, Wiley C. McMahan, a citizen of the United States, residing at Heflin, in the county of Cleburne and State of Alabama, have invented a new, original, and ornamental Design for a Draft Yoke, of which the following is a specification, reference being had to the accompanying drawing, forming part thereof.

Figure 1 is a view in rear elevation of a draft yoke, showing my new design.

Figure 2 is a view in top plan thereof.

Figure 3 is a side elevational view.

I claim:

The ornamental design for a draft yoke as shown.

WILEY C. McMAHAN.
